US00D881920S

(12) **United States Design Patent** (10) Patent No.: **US D881,920 S**
 Argo et al. (45) Date of Patent: **** Apr. 21, 2020**

(54) **DISPLAY SCREEN OR PORTION THEREOF WITH GRAPHICAL USER INTERFACE**

(71) Applicant: **Intuitive Surgical Operations, Inc.**, Sunnyvale, CA (US)

(72) Inventors: **Lauren L. Argo**, San Francisco, CA (US); **Jason S. LaFrenais**, San Jose, CA (US); **Oscar G. Salazar**, Sunnyvale, CA (US)

(73) Assignee: **INTUITIVE SURGICAL OPERATIONS, INC.**, Sunnyvale, CA (US)

(**) Term: **15 Years**

(21) Appl. No.: **29/665,533**

(22) Filed: **Oct. 4, 2018**

(51) LOC (12) Cl. **14-04**

(52) U.S. Cl.

USPC **D14/486**

(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a front view of a second embodiment thereof; and, FIG. 3 is a front view of a third embodiment thereof.

The long-dash/short-dash/short-dash broken lines shown in FIGS. 1-3 illustrate the display screen or portion thereof and form no part of the claimed design.

The even broken lines shown in FIGS. 1 and 2 illustrate portions of the graphical user interface and form no part of the claimed design.

1 Claim, 3 Drawing Sheets
